CLAIM

The ornamental design for a joint for above ground pool frame, as shown and described.

DESCRIPTION

FIG. 1 is a front perspective view of a joint for above ground pool frame showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The long-short broken lines within the openings depict boundaries that form no part of the claimed design. The evenly-sized broken lines depict portions of the joint for above ground pool frame that form no part of the claimed design.
